United States Patent Office

Des. 186,393
Patented Oct. 20, 1959

186,393

CUP RACK

Fred K. Osborne and Harold F. Spelts, San Diego, Calif.

Application November 24, 1958, Serial No. 53,513

Term of patent 3½ years

(Cl. D44—29)

Fig. 1

Fig. 2

Fig. 3

Fig. 4

Fig. 5

Figure 1 is a perspective view of a cup rack, showing our new design;

Figure 2 is a top plan view thereof;

Figure 3 is a side elevational view thereof;

Figure 4 is an end elevational view as taken from the left side of Figure 3; and

Figure 5 is a bottom plan view thereof.

We claim:

The ornamental design for a cup rack, as shown.
